VACUUM VESSEL

Ludwig Herrmann, Frankfort-on-the-Main, Germany, assignor to Kurt Adamczick and Willy List, Frankfort-on-the-Main, Germany

Application October 6, 1932, Serial No. 636,493
In Germany October 8, 1931

10 Claims. (CL 250—27.5) (313-74)

Vacuum tubes have already been proposed, in which both cathode rays and canal rays are directed towards a window for the discharge of electrons. Such vacuum tubes serve for carrying out chemical reactions. If an air current is conducted adjacent to the outer side of the window, nitrogen compounds form therein. The nature of the reaction thereby taking place has not yet been explained. The window is like the window in a Lenard tube. Consequently, electrons pass therethrough. The importance of the canal rays striking against the window has not yet been scientifically explained. It may be, that the canal rays cause the production of secondary rays which are important for the chemical reactions. In any case, it is necessary to direct canal rays, besides cathode rays, towards the Lenard window, as only then will the reactions take place. For these reactions the presence of Röntgen rays are probably also important. Röntgen rays are produced in the vacuum tube owing to the high potentials on the electrodes, without it being necessary to provide special equipments therefor. These Röntgen rays pass through the metal foil, forming the window of the vessel, into the reaction chamber and can there exert a certain influence on the reaction taking place.

The vacuum tubes hitherto proposed, in which both the cathode rays and the canal rays are directed against a window for the discharge of electrons, are of very complicated construction and extremely difficult to manufacture. The invention relates to a vacuum tube of the type in question and especially solves the problem of simplifying the construction and manufacture. The vacuum tube according to the invention is in the form of a long tube, in the middle portion of which a perforated cathode and a glowing cathode are arranged, whereas in the ends of the tube anodes are provided, that anode directed towards the electron current emanating from the glowing or incandescent cathode being of such shape, that the rays can strike onto the window situated behind this anode. The long tubular shape of the vacuum tube enables the impression of high potentials without difficulty. The spherical vacuum tubes hitherto proposed were provided for this purpose with electrode leading-in extensions and as each electrode requires one leading-in extension, the tube is expensive to manufacture and moreover it is difficult to fit the spherical middle portion with a large number of leading-in extensions. The simple construction of the tube according to the invention is

illustrated in longitudinal section in the only figure of the accompanying drawing.

In the middle portion of the tube 1 a perforated cathode 2 and a glowing or incandescent cathode 3 are arranged. The glowing cathode 3 is surrounded by a cylinder 3a made of metal and consists of a wire spiral coated with an alkaline earth metal oxide. The leading-in and leading-off of the heating current takes place through an extension 4. The heating current is supplied by a wire 5a and connected off by a wire 5b. An anode 6 provided with a known water cooling arrangement 7 cooperates with the perforated cathode 2. An electron current passes from the cathode 2 to the anode and canal rays, that is, chiefly swarms of positive ions, pass through the narrow passages 2a in the cathode 2 into the lower portion of the tube 1. A potential of about 250 kv is applied between the anode 6 and the cathode 2. The heating potential for the glowing cathode 3 is about 4 volts. The anode 6 co-operates with the glowing cathode 3. A flow of quick electrons passes from the glowing cathode 3 to the anode 6 and through a window 9 into the atmosphere or into the reaction chamber. The window 9 consists of a thin aluminum foil, which is arranged in front of a metal plate (not shown) perforated like a sieve. The anode 6, directed towards the flow of electrons emanating from the glowing cathode 3, must evidently be of such shape that the radiation can strike against the window 9 situated behind the anode 6. A hollow cylindrical shape has been found most suitable for the anode 6. In order to make the anode 6 as light as possible, it has rectangular apertures 6a. The window carrier 9a is provided with a cooling arrangement 9b for liquid, so as to prevent the window from being heated by the rays striking thereon to such an extent that it melts. A corresponding cooling arrangement 10 is located in the middle portion of the tube at the point where the cathodes 2 and 3 are arranged. Cooling liquid, e. g. water, is fed to the cooling arrangements 9b and 10 through the tubes 11 and 12 respectively. Holes 13a, 13b serve for connecting the window carrier 9a with the bottom portion of the tube 1 by means of bolts (not shown). Corresponding apertures 14a, 14b serve for the connection of the upper tube part accommodating the anode 6 with the lower tube part containing the anode 6. The lower part of the tube is provided with an evacuating socket 15 for connecting to a pump. The cathode 2 has a flange-like foot 2b which, together with the cathode 2, forms a partition dividing the tube in such a manner,

- that the upper tube space $1a$ and the lower tube space $1b$ intercommunicate only through the fine passages $1c$ in the perforated cathode. This subdivision of the tube causes a difference in pressure between the tube spaces $1a$ and $1b$, when the tube is connected to the pump, owing to the considerable drop in pressure caused by the passages $1c$. As the tube is connected to the pump by means of the socket 15 , the pressure in the tube space $1a$ is greater than in the tube space $1b$. The presence of a slightly higher pressure in the tube space $1a$ increases the production of canal rays. The discharge paths are surrounded by the glass cylinders 16 and $18a$ respectively. The casings of the tube may be of metal.
- Having now particularly described and ascertained the nature of my said invention, and in what manner the same is to be performed, I declare that what I claim is:
1. A vacuum tube for producing both cathode rays and canal rays and directing both said rays towards a Lenard window, the said vacuum tube having, in combination, a tubular member, a pierced cathode and an incandescent cathode mounted between the ends of said member, one anode being mounted on one end of said member and another anode being mounted on the other end of said member, and a Lenard window mounted on the end of said member opposite to said incandescent cathode.
2. A vacuum tube for producing both cathode rays and canal rays and directing both said rays onto a Lenard window adapted for the passage of electrons, the said vacuum tube having, in combination, two gas-discharge spaces both including means for the production of an electric discharge, and means for leading canal rays from one of said spaces to the other of said spaces, the vacuum in one of said spaces being lower than the vacuum in the other of said spaces.
3. A vacuum tube for producing both cathode rays and canal rays and directing both said rays onto a Lenard window adapted for the passage of electrons, the said vacuum tube having, in combination, two gas-discharge spaces, one of said spaces containing an anode and a perforated cathode co-operating therewith, the other of said spaces accommodating an incandescent cathode and an anode co-operating therewith, the vacuum in said latter space being lower than the vacuum in said first mentioned space, and the discharge space containing the incandescent Lenard cathode being provided with a window adapted for the passage of cathode rays.
4. A vacuum tube for producing both cathode rays and canal rays and directing both said rays to a Lenard window adapted for the passage of cathode rays, the combination, a tubular member, a perforated cathode subdividing said member into two discharge chambers, an anode in one of said chambers co-operating with said perforated cathode, and an incandescent cathode mounted adjacent to said perforated cathode in the other of said chambers, said latter chamber containing an anode co-operating with said incandescent cathode and being closed by a Lenard window adapted for the passage of cathode rays, and the chamber containing the incandescent cathode being provided with an evacuation pipe.
5. A vacuum tube for producing both cathode rays and canal rays and directing both said rays onto a Lenard window adapted for the passage of electrons, the combination, a tubular member, a

pierced cathode and an incandescent cathode mounted substantially in the middle of said member, anodes arranged on both ends of said member, said pierced cathode subdividing said member into two partitions that are connected with each other by the perforations of said pierced cathode only, the partition accommodating the incandescent cathode being provided with an evacuation pipe, and a Lenard window adapted for the passage of cathode rays.

6. A vacuum tube for producing both cathode rays and canal rays and directing both said rays to a Lenard window for the passage of cathode rays, the combination, a tubular member, a pierced cathode and an incandescent cathode mounted between the ends of said member, anodes mounted opposite to each of said cathodes, a Lenard window for the passage of cathode rays mounted opposite to said incandescent cathode, means for cooling said Lenard window, and means for cooling said tubular member, said latter means being mounted substantially where the cathodes are provided.

7. A vacuum tube for producing both rays of negative and positive electricity and directing both said rays to a Lenard window adapted for the passage of cathode rays, the said vacuum tube, having in combination, a tubular member, a pierced cathode and an incandescent cathode mounted between the ends of said member, anodes mounted substantially on the ends of said member, and a Lenard window for the passage of cathode rays mounted opposite to said incandescent cathode, the anode mounted between said cathode and said Lenard window being cylindrical.

8. A vacuum tube comprising a tubular member, a pierced cathode and an incandescent cathode in the member between the ends thereof, and two anodes in the member disposed at the ends thereof, the tubular member having a Lenard window at the end opposite to the incandescent cathode.

9. A vacuum tube producing cathode rays and canal rays for carrying out chemical reactions comprising a tubular bulb, a pierced cathode and an incandescent cathode mounted in the bulb between the ends thereof, and two anodes in the bulb disposed at the ends thereof, the bulb having at the end opposite to the incandescent cathode a wall portion permeable for the radiation produced therein by the co-action of the cathode rays and canal rays.

10. A vacuum tube for producing both cathode rays and canal rays and directing both said rays onto the same portion of the wall of said tube, said portion being permeable for the radiation produced by the co-action of the cathode rays and canal rays, comprising, in combination, two gas-discharge chambers both including electrodes for the production of an electric discharge, said electrodes being mounted to produce cathode rays and canal rays of the same direction, and means permitting to flow one kind of said rays from one of said chambers to the other, said ray-permeable wall portion of the tube being provided on the discharge chamber wherein both kinds of rays are united, and the vacuum in the cathode-ray-producing chamber being higher than the vacuum in the canal-ray-producing chamber.

LUDWIG HERRMANN.
